(57) **CLAIM**

The ornamental design for a work assistant, as shown and described.

DESCRIPTION

FIG. 1 is a top and left front perspective view of a work assistant showing my new design;

FIG. 2 is a left side elevational view thereof when in use; and,

FIG. 3 is a right side elevational view thereof in a second position, the left side view thereof being a mirror image of the side view shown.

The individual and lap top computer shown in FIG. 2 are shown for illustrative purposes only and form no part of the claimed invention.

1 Claim, 3 Drawing Sheets
